HATCH COVER

Ernest Willison, Sewickley, Pa., assignor to Dravo Corporation, a corporation of Pennsylvania

Continuation of application Serial No. 228,387, September 3, 1938. This application December 8, 1939, Serial No. 308,188

6 Claims. (Cl. 114—202)

This invention relates to hatch covers, such as are provided for hatchways that open through the decks of ships. The objects in view are simplicity of structure, economy of space, and facility in operation. This application is a continuation of application 228,387 filed September 3, 1938.

In the accompanying drawing Fig. I is a view in side elevation, showing fragmentarily a hatchway and, associated with it in folded or inactive position, and in side elevation, the hatch cover of my invention. In this view certain supporting members appear in section. Fig. II is a fragmentary view in plan. Fig. III is a diagrammatic view, illustrating the movement of the component parts of the hatch cover, in passing between inactive to active positions. Fig. IV is a view to larger scale, showing in cross-section a rail that caps the hatchway coaming and in elevation a block that is a feature of the invention in assembly with the rail. Fig. V is a view in section, on the plane indicated at V—V, Fig. IV.

A hatchway, whose opening through a deck is indicated at H, Fig. I, is provided along opposite parallel sides with rails in the form of inverted channels 1 that cap the hatch coaming. The hatchway cover is made up of a plurality of substantially duplicate panels 2 that rest at their ends, when, in closed position, upon the upper surfaces of the opposite channels 1. The cover panels are provided at their two ends with rollers 3 and these rollers are extensible vertically from the panels, to the end that the panels when in position above the hatchway may alternately rest with their edges upon the channels 1, to make tight and stationary closure, or that they may be raised, to rest upon their rollers, and to be readily movable upon the rollers longitudinally of the channels. The structure in this regard may be such as that shown in an application filed September 1, 1938, by Albert J. Dawson and Ernest Willison (the applicant here), Serial No. 227,932 which matured into Patent 2,194,012, March 19, 1940. With reference to Fig. IV, it may be understood that the panels 2 will rest by their rollers upon the free right-hand portion of the upper surface of the channel 1. This free, right-hand portion will be understood to be the outer portion of the channel surface, and this portion, together with the complementary left-hand portion of the duplicate channel that caps the coaming on the opposite side of the hatchway, constitute the runway for the roller-equipped cover panels (cf. Fig. II).

Upon the deck are mounted pairs of blocks.

The preferred structure is that illustrated. The channels 1 extend to the side of the hatchway (to the left, Figs. I and II), beyond the limit of the hatchway opening H, and in such extended portions are equipped with pairs of hinge blocks. The blocks, pair by pair, stand opposed on the two channels 1. The channels are slotted, as indicated at 10 (cf. Fig. II). The blocks (Figs. IV and V) are formed to engage the slots, to straddle the outer margins of the channels, and to be secured in place by locking wedges. Each block is formed of two plates 4 and 5 that, standing apart, carry between them a pintle 6. The plate 4 is provided with a tongue-like extension 41 that in the assembly extends through a slot 10 and projects downward from channel 1; plate 5 in the assembly abuts upon the outer flange of the channel, and extends downward beyond the edge of the flange; and the two plates in their downward extensions are provided with aligned slots, for the reception of a wedge 7. The plate 4 is shouldered at 42, to rest from above squarely upon the upper surface of the channel; and to the plate 5 on its inner face a block 51 is welded, and by this block plate 5 also rests squarely upon the channel. To the inverted channel 1 a narrower channel 11 in upright position is applied from below and welded to place. The nether face of this channel 11, when applied, extends in common plane with the edges of the marginal flanges of channel 1. The channel 11 may be continuous or intermittent in its longitudinal extent; it underlies the slots 10, and is itself correspondingly slotted. The nether face of channel 11 and the edge of the outer flange upon channel 1 afford bearings for the wedge 7. When the block has been applied, in the position shown in Figs. IV and V, the wedge 7, engaging along one edge the channel surfaces specified and along the opposite edge the bottoms of the slots in the downward extensions of plates 4 and 5, is driven home to secure the block in place.

Each panel 2 of the hatchway cover carries a pair of bearing blocks 8, that correspond in shape and in position to the pairs of channel-borne blocks already described. Referring particularly to Fig. II, and comparing it with Figs. IV and V, it will be seen that the panel 2 on the right bears at its left end a pair of blocks 8; and that these blocks are spaced apart at an interval greater than the length of the panel that bears them (the length of the panel being its vertical extent, as seen in Fig. II). The blocks of the co-operating deck-borne pair are correspondingly spaced.

The blocks 8 are bifurcated, as shown, so that as the panel travels to the left they will engage, and as the panel travels to the right they will separate from, the pintles 6 of a pair of channel-borne blocks. When such engagement is made, the interengaged blocks constitute hinges upon which the panel may be swung, from the full-line position, Fig. III, to the dotted-line position.

The blocks 8 of each pair are borne by the panel at its ends, and they project laterally from the panel along one side (to the left, Figs. I, III, and V). In consequence of the spacing specified, the panels may come together in edge-to-edge union, as indicated in Fig. II. The blocks upon the channels 1 are correspondingly spaced apart; they stand along the outer margins of channels 1.

In operation, when the hatchway is to be opened and the cover carried out of the way, each cover panel in turn, being separated from the next adjacent panel and being in raised position and resting on its rollers, is rolled from right to left, Fig. I, until its blocks 8 come to engagement with the pintles 6 of a pair of the channel-borne blocks. The panel then is swung on the hinges so formed, from horizontal to vertical position. Fig. I shows five panels, and it may be assumed that they together constitute the complete hatchway cover. At the beginning of the operation of opening of the hatchway it may be understood that one pair of blocks and no more (the pair at the extreme left, Figs. I and II) is in position on channels 1. (This pair of blocks, indeed, may be permanently secured to the channels 1.) The first panel in the left to right succession is then rolled from the broken-line position until its blocks 8 engage the pintles 6 of the channel-borne blocks. The panel then is swung on its hinges to the full-line position. A pair of blocks is then applied to and secured in position in the next adjacent pair of slots 10 to the right; and, when this has been done, the second panel is rolled to engagement with the pintles of this second pair of blocks and swung into vertical position; and so panel after panel is rolled aside and swung out of the way, until the whole cover is so disposed of. Fig. I affords indication that the spacing of the slots 10 may slightly exceed the over-all depth of the panels, and in consequence the succeeding panels of the collapsed assembly are progressively canted to the left, and the whole rendered secure in collapsed position.

When the hatchway is to be closed again the steps described are reversed. The panels one by one, beginning at the right, are swung to horizontal position, and rolled to place over the hatchway. The channel-borne blocks are removed pair by pair to allow free course for the next succeeding panel.

Suitable weather-tight closure will be provided for the panels at the seams, where the panels in closed position meet side by side, and suitable weather-tight closure will be provided for the cover, when in active position, at the margin of the hatchway opening.

It is manifest that either member of the co-operating pairs of blocks may carry the pintles of the hinge union and the other the bifurcations.

I claim as my invention:

1. In a deck structure that includes a hatchway and a hatch cover consisting of a plurality of panels equipped with rollers and movable upon their rollers upon the deck between hatch-covering and hatch-uncovering positions, the invention herein described which consists in the com-

bination with the structure defined of a plurality of pairs of blocks borne pair by pair upon said panels at the side of the panel which in the advance of the panel to hatch-uncovering position constitutes the leading edge thereof, and a corresponding plurality of pairs of blocks borne pair by pair upon the deck, the panel-borne blocks and the deck-borne blocks constituting complementary parts of hinge connections that are completed and separated again by the movement of the panels upon their rollers.

2. In a deck structure that includes a hatchway and a hatch cover consisting of a plurality of panels equipped with rollers and movable upon their rollers upon the deck between hatch-covering and hatch-uncovering positions, the invention herein described which consists in the combination with the structure defined of a plurality of pairs of bifurcated blocks borne pair by pair upon said panels and a corresponding plurality of pairs of pintle-equipped blocks borne pair by pair upon the deck, the panel-borne blocks and the deck-borne blocks constituting complementary parts of hinge connections that are completed and separated again by the movement of the panels upon their rollers.

3. In a deck structure that includes a hatchway, two rails extending in parallelism along opposite ends of the hatchway and beyond the hatchway to one side thereof, and two cover panels equipped with rollers and movable upon its rollers along the runway afforded by the said rails between hatch-covering and hatch-uncovering positions, the invention herein described which consists of the combination, with the structure defined, of two pairs of blocks borne pair by pair by the said panels, and two pairs of blocks borne pair by pair by the deck, the panel-borne blocks and the deck-borne blocks constituting complementary parts of hinge connections that are completed and separated again by the movement of the panels along the runway, the blocks borne by the panel that is second in the order of advance of the panels from hatch-covering to hatch-uncovering position extending from the side thereof which in the advance of the panel to hatch-uncovering position constitutes its leading edge, and being spaced apart at an interval greater than the length of the panel, and the complementary pair of deck-borne blocks being correspondingly spaced.

4. In a deck structure that includes a hatchway, two rails extending in parallelism along opposite ends of the hatchway and beyond the hatchway to one side thereof, and two cover panels equipped with rollers and movable upon its rollers along the runway afforded by the said rails between hatch-covering and hatch-uncovering positions, the invention herein described which consists of the combination, with the structure defined, of two pairs of blocks borne pair by pair by the said panels, and two pairs of blocks borne pair by pair by the deck, the panel-borne blocks and the deck-borne blocks constituting complementary parts of hinge connections that are completed and separated again by the movement of the panels along the runway, the panel-borne blocks extending from one side of each panel and the blocks of each pair being spaced apart at an interval greater than the length of the panel, the pairs of deck-borne blocks being correspondingly spaced and the pair of deck-borne blocks that is nearer to the hatchway being 75.

removable and replaceable in their mounting upon the deck.

5. In a deck structure that includes a hatchway, two rails extending in parallelism along opposite ends of the hatchway and beyond the hatchway to one side thereof, and two cover panels equipped with rollers and movable upon its rollers along the runway afforded by the said rails between hatch-covering and hatch-uncovering positions, the invention herein described which consists of the combination, with the structure defined, of two pairs of blocks borne pair by pair by the said panels and two pairs of blocks borne pair by pair by the said rails at the outer margins thereof and beyond the runway for the roller-equipped panels, the panel-borne blocks and the rail-borne blocks constituting complementary parts of hinge connections that are completed and separated again by the movement of 20 the panels along the runway, the blocks of the second panel in the order of advance to hatch-uncovering position extending from the side

thereof and being spaced apart at an interval greater than the length of the panel, and the pair of rail-borne blocks nearer the hatchway being removably borne by the rails.

6. In a deck structure that includes a hatchway and a hatch cover consisting of a plurality of panels equipped with rollers and movable upon their rollers upon the deck between hatch-covering and hatch-uncovering positions, the invention herein described which consists in a plurality of 5 pairs of blocks borne pair by pair upon the deck, and in a succession of pairs, to one side of the hatchway, the number of the pairs of blocks in such succession corresponding to the number of panels of the hatch cover, each panel being 10 equipped at one end with a pair of blocks, the panel-borne blocks being adapted in the moving of the panels to come to engagement with and to form pivotal engagement with the deck-borne 15 blocks.

20 ERNEST WILLISON.
